Their Attorney.

UNITED STATES PATENT OFFICE.

ARTHUR P. YOUNG, OF KENILWORTH, AND ALEXANDER H. ST. C. WATSON, OF COVENTRY, ENGLAND, ASSIGNORS TO GENERAL ELECTRIC COMPANY, A CORPORATION OF NEW YORK.

ELECTROMAGNETIC RELAY.

1,190,066.

Specification of Letters Patent.

Patented July 4, 1916.

Application filed May 21, 1915. Serial No. 29,691.

To all whom it may concern:

Be it known that we, ARTHUR P. YOUNG, a subject of the King of Great Britain, residing at "Dovetail", Priory Road, Kenilworth, in the county of Warwick, England, and ALEXANDER H. ST. C. WATSON, a subject of the King of Great Britain, residing at Earlsdon, Coventry, in the county of Warwick, England, have invented certain new and useful Improvements in Electromagnetic Relays, of which the following is a specification.

This invention relates to electromagnetic relays, and has for its object to produce a relay of simple construction in which a plurality of movable armatures may be simultaneously actuated from a single coil and in which a strong pull may be obtained with the minimum voltage on which it is desired to operate the same.

Electromagnetic relays are provided for various purposes, and in particular for use with voltage regulators of the "Tirrill" type. In the patent to Tirrill, #1,101,670, there is shown a type of relay wherein a plurality of cores and associated movable armatures may be magnetized from a pair of coils. In this patent the cores are E-shaped and the magnetic pull is distributed along the length of the armature arm.

Our invention has particular relation to an improved relay of this type and its construction will be more readily understood by reference to the accompanying drawing, in which:

Figure 1 is a diagrammatic view illustrating the connections of the relay when used in conjunction with a Tirrill regulator; Fig. 2 is a plan view of a fragment of a coil of such a relay provided with two cores; and Fig. 3 is a cross-section on the line 3—3 of Fig. 2.

We shall first describe the operation of a relay of this type in connection with a Tirrill regulator operating upon the field of an exciter, and then describe the particular construction which constitutes our invention. An alternating current generator 10 is provided with a field winding 11 which is excited from the exciter 12; this exciter in turn being provided with a field winding 13 in series with which is a resistance 14. The regulator illustrated is provided with movable contact arms 20 and 21, the arm 20

moving in response to the varying strengths of the coil 22 energized in proportion to the exciter voltage, while the arm 21 moves in response to the varying strengths of the coil 23 energized in proportion to the alternating current generator voltage. The relay 30 is then arranged with its contacts 31 short-circuiting the resistance 14, the usual condenser 15 being shunted across the said contacts to minimize the sparking. This relay is preferably wound differentially, one winding 32 being permanently connected with the exciter brushes, while the winding 33, arranged in opposition thereto, is so connected that it will be energized when the contacts carried on the arms 20 and 21 close. A suitable resistance 34 is provided to reduce the flow of current in the windings of the relay.

The windings 32 and 33 are preferably wound non-inductively in a single coil having a considerable internal diameter and a relatively small cross-section. Surrounding one side of this coil are a plurality of magnetic cores 35, forming a substantially closed rectangle, the ends 36 of which project outwardly so that the magnetic circuit is incomplete. A movable armature 37 is then arranged to be attracted by the outwardly projecting ends 36 of the core. This armature is preferably made in the form of a bell crank lever pivoted to the supporting frame-work 40, and provided with a spring 38 arranged to hold the armature away from the projecting ends 36 of the core. This will result in inserting the resistance 14 in the exciter field and thereby produce the desired regulation in a well understood manner.

Although we have herein described our device in its particular application to use with a voltage regulator, it will be understood that it is in no wise limited to such a use, and is applicable to any case where it is desired to attract a plurality of movable armatures simultaneously. By means of the particular shape of the magnetic core used in our invention, it will be seen that we are enabled to dispense with one of the coils of the relay illustrated in the patent to Tirrill above mentioned, and that, in addition, we have concentrated the flux at a point removed from the pivot of the movable armature and thereby increased the effective turning moment. This combination results in not only simplifying the construction, but also in increasing the pull obtained with the minimum voltage at which it is desired to operate. Since in the particular application herein described the exciter voltage varies over a considerable range, it will be seen that this feature becomes particularly important, since it enables us to design the spring 38 with considerably greater strength than formerly. This results in increasing the speed with which the relay operates to close the contacts 31 when both windings of the coil are energized.

While we have herein shown and described one particular form of our invention, we wish it understood that we are not limited thereto and that our invention, while extending to all the details of construction, is only limited by the scope of the appended claim.

What we claim as new and desire to secure by Letters Patent of the United States, is,—

An electromagnetic relay comprising a differentially wound coil of substantial internal diameter, a plurality of magnetic cores substantially surrounding one side of said coil to form an incomplete magnetic circuit having two projecting closely adjacent ends, a movable armature for each core pivotally mounted at a point remote from said ends and adapted to close said magnetic circuit when attracted by said core, said armature carrying a contact, and a fixed contact coöperating therewith.

In witness whereof, we have hereunto set our hands this 4th day of May, 1915.

ARTHUR P. YOUNG.

ALEXANDER H. ST. C. WATSON.
